GREEN AZODYESTUFFS

Konrad Stenger and Carl Erich Müller, Frankfort-on-the-Main, Germany, assignors to General Aniline Works, Inc., New York, N. Y., a corporation of Delaware

No Drawing. Application May 20, 1932, Serial No. 612,633. In Germany May 26, 1931

10 Claims. (Cl. 260—84)

The present invention relates to new green azodyestuffs which can be produced on fibrous materials made of cellulose esters and ethers and to the dyed materials, more particularly it relates to azodyestuffs which can be obtained by dyeing the said fibrous materials with a water-insoluble para-amino-mono azodyestuff, free from sulfonic and carboxylic acid groups, of the general formula:

wherein R and R₁ represent radicals of the benzene series, the radical R being at least once substituted by an alkoxy group, and the X's represent lower saturated alkyl, cyclohexyl or benzyl radicals or jointly with the nitrogen atom represent the morpholine radical diazotizing the amino-mono-azodyestuff on the fiber and developing with a coupling component of the general formula:

wherein Y stands for hydrogen and Y₁ for an alkoxy or alkyl group, or Y and Y₁ jointly represent a benzene nucleus attached to the naphthalene nucleus.

The dyeings thus obtained possess green shades of good fastness properties.

The new dyestuffs thus produced on cellulose esters or ethers possess the following general formula:

wherein R, R₁, the X's and Y and Y₁ have the above meanings:

The following examples serve to illustrate the invention, but they are not intended to limit it thereto:

(1) A dye bath is prepared by dissolving 3 grams of 3-methoxy-4-aminobenzene-azo-4'-dimethyl-aminobenzene in 30 liters of water while adding a sufficient quantity of hydrochloric acid to obtain a solution. In this solution 1000 grams of acetate silk are dyed while slowly heating for $\frac{3}{4}$ hour at 70° C.—75° C. After having handled the goods in the dye bath for $\frac{1}{4}$ hour, 5% of sodium acetate, calculated upon the weight of the goods, are advantageously added to the bath. Thereupon the material is rinsed, the dyestuff is diazotized on the fiber in the usual manner in a

freshly prepared bath and the dyeing is then developed for 1 hour at 50° C. in another bath having a weak acetic acid reaction and containing 3 per cent of 6-methoxy-2,3-hydroxynaphthoic acid, calculated upon the weight of the goods.

The azodyestuff may also be used in the form of a suspension or emulsion in a soap bath or in the presence of any other dispersion medium. There is obtained a vivid green dyeing of good fastness and discharge properties. The dyestuff produced on the fiber corresponds with the following formula:

(2) By using in Example 1 instead of the azodyestuff mentioned therein, 4-amino-2,5-dimethoxybenzene-azo-4'-diethylaminobenzene there is obtained with the same developing component a beautiful green dyeing of valuable properties. The dyestuff produced on the fiber corresponds with the following formula:

(3) Acetate silk is dyed with the azodyestuff mentioned in Example 1 and there is used as developing component 6-methyl-2,3-hydroxynaphthoic acid. There is obtained a bluish-green dyeing of good fastness properties. The dyestuff thus produced on the fiber corresponds with the following formula:

(4) A dye bath is prepared by dissolving 3 grams of 2,5-dimethoxy-4-aminobenzene-azo-4'-aminotetrahydronaphthalene in 30 liters of water while adding a sufficient quantity of hydrochloric acid to obtain a solution. In this solution 1000 grams of acetate silk are dyed while slowly heating for $\frac{3}{4}$ hour at 70° C.—75° C. After having handled the goods in the dye bath for $\frac{1}{4}$ hour, 5% of sodium acetate, calculated upon the weight of the goods, are advantageously added to the bath.

bath. Thereupon the material is rinsed, the dye-stuff is diazotized on the fiber in the usual manner in a freshly prepared bath, and the dyeing is then developed for 1 hour at 50° C. in another bath having a weak acetic acid reaction and containing 3% of 6-methoxy-2,3-hydroxynaphthoic acid calculated upon the weight of the goods. There is obtained a beautiful green dyeing. The dyestuff produced on the fiber corresponds with the following formula:

20 Instead of dissolving the dyestuff in hydrochloric acid, it may also be used in the form of a suspension or emulsion in a soap bath, the dyestuff may then be diazotized and the dyeing be developed as above described.

(5) By using in Example 4 as the developing component 6-methyl-2,3-hydroxynaphthoic acid, there are obtained bluish-green dyeings. The dyestuff produced on the fiber has the following formula:

(6) By using in Example 4 instead of the dye-stuff mentioned therein 3 grams of 2-methoxy-4-amino-benzene-azo-4'-amino-tetrahydronaphthalene and developing by means of 6-methoxy-2,3-hydroxynaphthoic acid, there are obtained Russian green dyeings. The dyestuff produced on the fiber has the following formula:

(7) By using a dye bath containing 5 grams of 2,5-dimethoxy-4-aminobenzene-azo-4'-dimethyl-aminotetrahydronaphthalene in 30 liters of water and developing with 6-methoxy-2,3-hydroxy-55 naphthoic acid there are obtained bluish-green dyeings. The dyestuff thus produced on the fiber corresponds with the following formula:

(8) A dye bath is prepared by dissolving 3 grams of 3-methoxy-4-aminobenzene-azo-4'-dimethylaminobenzene in 30 liters of water while adding a sufficient quantity of hydrochloric acid 70 to obtain a solution. In this solution 1000 grams of acetate silk are dyed while slowly heating for $\frac{3}{4}$ hour at 70° C.-75° C. After having handled the goods in the dye bath for $\frac{1}{4}$ hour, 5 per cent of sodium acetate, calculated upon the weight 75 of the goods, are advantageously added to the

bath. Thereupon the material is rinsed, the dye-stuff is diazotized on the fiber in the usual manner in a freshly prepared bath and the dyeing is then developed for 1 hour at 50° C. in another bath having a weak acetic acid reaction and containing 3 per cent of 2,3-hydroxyanthracene carboxylic acid calculated upon the weight of the goods. There is obtained a beautiful green dyeing. The dyestuff produced on the fiber has the following formula:

(9) By using instead of the azodyestuff mentioned in Example 8, 3 grams of 2,5-dimethoxy-4-aminobenzene-azo-4'-diethylaniline there is obtained a yellowish green dyeing. 20

(10) Instead of the azodyestuffs mentioned hereinbefore, the following ones may likewise be used: 25

3-methoxy-4-aminobenzene-azo-4'-N-methyl-cyclohexylamino-benzene of the following formula: 35

4-amino-2,5-dimethoxybenzene-azo-4'-di-n-butylamino-benzene of the following formula:

4-amino-2,5-dimethoxybenzene-azo-4'-phenyl- 50
morpholine of the following formula:

3-methoxy-4-aminobenzene-azo - 4'-dimethyl- 6
amino-2'-methylbenzene of the following for-
mula:

3-methoxy-4-aminobenzene-azo-4'-diethylamino-2'-methylbenzene of the following formula:

4-amino-2,5-dimethoxybenzene-azo-4'-dimeth- 7

ylamino-2'-chlorobenzene of the following formula:

10 4-amino-2,5-dimethoxybenzene-azo - 4'-dibenzylamino-benzene of the following formula:

20 The mono-azo-dyestuffs used may be prepared, for instance, by coupling substituted para-nitranilines with the corresponding aminobenzenes or amino- or dialkylamino-tetrahydronaphthalenes being disubstituted in the amino group and thereupon reducing the nitro group to the amino group.

We claim:

25 1. The green azo-dyestuffs of the general formula:

35 wherein R and R₁ represent radicals of the benzene series, the radical R being at least once substituted by an alkoxy group, the X's represent lower saturated alkyl, cyclohexyl or benzyl radicals or jointly with the nitrogen atom represent the morpholine radical, Y stands for hydrogen and Y₁ for an alkoxy or alkyl group or Y and Y₁ 40 jointly represent a benzene nucleus attached to the naphthalene nucleus, which dyestuffs when produced by combining the components on fibrous materials made of cellulose esters and ethers yield green dyeings of good fastness properties.

45 2. The green azo-dyestuffs of the general formula:

55 wherein the X's stand for lower saturated alkyl radicals, R₁ for a radical of the benzene series,

at least one of the Z's for an alkoxy group and the other for hydrogen, and Y₁ for an alkoxy group, which dyestuffs when produced by combining the components on fibrous materials made of cellulose esters and ethers yield green dyeings 5 of good fastness properties.

3. The green azo-dyestuff of the formula:

which dyestuff, when produced by combining the components on acetate silk yields a vivid green dyeing of good fastness and discharge properties.

4. The green azo-dyestuff of the formula:

which dyestuff, when produced by combining the components on acetate silk yields a beautiful green dyeing of valuable properties.

5. The green azo-dyestuff of the formula:

which dyestuff, when produced by combining the components on acetate silk yields a green dyeing of good fastness properties.

40 6. Fibrous materials, dyed with dyestuffs claimed in claim 1.

7. Fibrous materials, dyed with dyestuffs claimed in claim 2.

8. Fibrous materials, dyed with a dyestuff claimed in claim 3.

9. Fibrous materials, dyed with a dyestuff 50 claimed in claim 4.

10. Fibrous materials, dyed with a dyestuff claimed in claim 5.

KONRAD STENGER.

CARL ERICH MÜLLER.
